UNITED STATES PATENT OFFICE

MICHAEL A. DAVITT, OF HEMPSTEAD, NEW YORK

DESIGN FOR A SEWING CABINET

Application filed May 19, 1932. Serial No. 43,842. Term of patent 3½ years.

To all whom it may concern:

Be it known that I, MICHAEL A. DAVITT, a citizen of the United States, residing at Hempstead, Long Island, in the county of Nassau and State of New York, have invented a new, original, and ornamental Design for a Sewing Cabinet, of which the following is a specification, reference being had to the accompanying drawing, forming part thereof.

cabinet in closed position, showing my new design,

Figure 2 is a top plan view thereof, and Figure 3 is a perspective view showing the sewing cabinet in an open position.

I claim:—

The ornamental design for a sewing cabinet, as shown.
